UNITED STATES PATENT OFFICE.

CHRISTOPHER C. ATKINSON, OF HAWKINSVILLE, GEORGIA.

RAILROAD-CROSSING SIGNAL.

Application filed March 30, 1923. Serial No. 628,822.

To all whom it may concern:

Be it known that I, CHRISTOPHER C. ATKINSON, a citizen of the United States, residing at Hawkinsville, in the county of Pulaski and State of Georgia, have invented certain new and useful improvements in Railroad-Crossing Signals; and I do hereby declare the following to be a full, clear, and exact description of the invention, 10 such as will enable others skilled in the art to which it appertains to make and use the same.

The present invention relates to railroad crossing signals, and aims to provide a novel 15 and improved signal mechanism for the intersection of a highway and railroad to prevent accidents.

Another object of the invention is the provision of a novel signal device which 20 can, if desired, be disposed across the highway or road, and which has normally raised signalling means adapted to move downwardly by gravity, means being provided for holding the signalling means in lowered 25 displaying position for a period of time so as to prevent the return of the signalling means until released.

A further object is the provision of novel 30 mechanism for automatically controlling the signalling means operated by trains approaching and leaving the crossing, so that the signal apparatus requires no manual actuation or attention, to eliminate the necessity for a watchman or attendant.

With the foregoing and other objects in 35 view, which will be apparent as the description proceeds, the invention resides in the construction and arrangement of parts, as hereinafter described and claimed, it 40 being understood that changes can be made within the scope of what is claimed, without departing from the spirit of the invention.

The invention is illustrated in the accompanying drawings, wherein—

Figure 1 is a plan view of the signal 45 mechanism.

Fig. 2 is a vertical section on the line 2-2 of Fig. 1 showing the signal device at the crossing.

Fig. 3 is an elevation of such signal 50 device showing one of the signal plates swung down to signalling position.

Fig. 4 is an elevation of one of the actuating 55 devices associated with a rail of the track.

Fig. 5 is a vertical section on the line 5-5 of Fig. 4.

Fig. 6 is an elevation of the device shown in Fig. 4 looking in the opposite direction.

The signal device, which is located at the 60 crossing, comprises a pair of posts 10 spaced apart transversely of the highway or road, and supporting an overhead frame 11 which preferably extends across or bridges the road, so that the signal device is disposed 65 across the road for the passage of traffic under the signal members. The frame 11 has a rod 12 disposed transversely of the road substantially parallel with the track, and signal plates 13 and 13' are hinged to 70 the rod 12 and are normally swung apart to opposite positions within the frame 11. Said plates contain suitable legends or signals, so that when either plate is swung 75 downwardly, it will provide a clear and effective warning, and if the device is disposed across the road, the signal plate or member will be disposed across the road, as seen in Fig. 3, to stop traffic. The signal plate or member when in lower signalling position, 80 may even provide an obstruction to prevent traffic moving across the track.

As will hereinafter appear, the plates or members 13 and 13' are spring-actuated to move them to raised positions when released, 85 and in order to hold the plates in lowered position, latches or hooks 14 and 14' are pivoted to the posts 10 to engage the plates 13 and 13', respectively, when they swing 90 downwardly.

The actuating means include cables or flexible elements 15 and 15' attached to the plates 13 and 13', respectively, and passing over the pulleys 16 and 16' carried by the frame 11, and also passing across guide 95 pulleys 17 and 17'. Said cables when pulled away from the signal device will raise the plates, and when said cables are slackened, the plates will swing downwardly by gravity to signalling position. Similar cables or 100 flexible elements 18 and 18' are connected to the latches 14 and 14', respectively, and pass over pulleys 19 and 19' carried by the frame 11, whereby when the cables 18 and 18' are pulled, the latches are disengaged 105 from the plates.

Actuating devices for the cables are associated with the track at opposite sides of and at suitable distances from the highway or road, and are suitably mounted on the 110

track. As shown, said devices are mounted on base plates 20 secured between the cross ties. One device includes the parallel rock shafts 21 and 22' extending under a rail of the track, and the other device comprises the corresponding rock shafts 21' and 22 extending transversely under the rail. The plates 20 have bearings 23 in which the shafts are journaled. The shafts 21 and 21' are provided at their outer ends, at the outside of the track, with the upwardly projecting arms 25 and 25', respectively, to which the cables 15 and 15' are connected, and the shafts 22 and 22' have the upwardly projecting arms 24 and 24', respectively, to which the cables 18 and 18' are connected. The shafts 22 and 22' are provided at their inner ends with upwardly extending arms 26 and 27 having their upper terminals disposed at the inner side of the rail and offset adjacent to the tread of the rail to be engaged by the wheels of the train, for swinging or tilting the arms 26 and 27 in the direction in which the train is moving, both arms 26 and 27 being moved in either direction. The inner ends of the shafts 21 and 21' have the upwardly extending arms 28 and 28', respectively, at the inner side of the rail, and said arms 28 and 28' have the portions 30 29 extending toward the rail across the arms 26 and 27 at those sides of the last named arms nearest the crossing, whereby the arms 28 and 28' are swung by and with the arms 26 and 27 when the last named arms are 35 swung or tilted in the direction of the crossing, whereas the arms 28 and 28' are not swung when the arms 26 and 27 are tilted away from the crossing.

Suitable springs 30 are provided for the arms 24 and 24' to normally retain them in vertical or intermediate position, and permitting said arms to swing or tilt in either direction, and suitable springs 31 are connected to the arms 25 and 25' to return them to vertical position, thereby pulling the cables 15 and 15' for raising the plates 13 and 13'. The springs 31 therefore normally support the plates 13 and 13' in raised position.

50 The parts 13, 14, 15, 16, 17, 18, 19, 21, 22, 24, 25 and 28 are for traffic in one direction only (from the right to the left in Fig. 1), while the other corresponding parts having the same reference numerals with prime marks are for traffic in the opposite direction, the arms 26 and 27 being operable for traffic in both directions. The mechanism, as shown, is for a single track in which traffic runs in both directions on the same track.

55 60 In operation, assuming that a train is approaching the crossing from the right in Fig. 1, when the first wheel of the train strikes the arm 26, such arm is swung toward the crossing, and in contacting with the arm 28, will also swing said arm toward

the crossing, thereby slackening the cables 15 and 18'. The cable 15 being slackened will permit the signal plate 13 to swing downwardly, and it will be engaged and held by the latch 14, as seen in Fig. 3. This 70 displays a warning signal across the road to indicate that a train is approaching the crossing. When the train leaves the crossing the first wheel which contacts with the arm 27 will swing said arm away from the crossing, thereby swinging the arm 24 in the same direction, and pulling the cable 18 so as to swing the catch 14 to release the plate 13, whereby the spring 31 of the lever 25 will return the lever 25 and plate 13 to 80 normal position, thereby clearing the signal device automatically.

When a train approaches the crossing from the opposite direction, the arm 27 is 85 swung to contact with and swing the arm 28', so as to slacken the cable 15' and to permit the signal plate 13' to swing downwardly. The latch 14' engages the plate 13' and holds it in signalling position until the train passes the arm 26 and swings said arm away from the crossing, so as to pull the cable 18', and disengage the latch 14' from the plate 13', said plate then being 90 swung upwardly by the spring 31 of the arm 24.

Although the arms 26 and 27 are oscillated by the wheels of the trains, the arms 28 and 28' and the corresponding arms 25 and 25' are held in their displaced positions, when moved by the arms 26 and 27, respectively, because the catches 14 and 14' holding the plates 13 and 13' down, will prevent the cables 15 and 15' from being pulled back by the springs 31, until the train has passed and left the crossing. This will avoid the continued oscillation of the arms 28 and 28', and corresponding parts, by all of the wheels of the train, and only the arms 26 and 27' and corresponding arms 24 and 24' will be oscillated by the successive wheels.

Having thus described the invention, what is claimed as new is:—

1. A signal device for a railroad crossing comprising an overhead frame, a signal plate hingedly connected with the frame to swing upwardly within the frame and to swing downwardly to signalling position, the axis of swinging motion of said plate being substantially parallel with the track, and means for swinging said plate.

2. A signal device for a railroad crossing comprising an overhead frame having a rod therein substantially parallel with the track, opposite signal plates hingedly connected with said rod to swing upwardly within the frame and to swing downwardly to signalling position, and means for swinging said plates within the frame.

3. A signal device comprising a frame, a

signal member mounted in the frame to move downwardly to signalling position, means for normally raising said signal member out of signalling position and operable

5 to permit the signal member to move downwardly, and a latch to engage the signal member and hold it in lowered signalling position against the action of said means.

4. A signal device comprising a pair of 10 posts, an overhead frame carried by said posts having a rod therein, opposite signal plates hingedly connected to said rod, means connected to the plates for swinging them upwardly within the frame and operable to

15 permit the plates to swing downwardly to signalling position, and latches carried by the posts for engaging said plates in their lowered positions.

5. A signal mechanism including a movable 20 signal member to be disposed at a railroad crossing, a latch for holding the signal member in signalling position, actuating devices associated with the railroad track at opposite sides of the crossing, an operative 25 connection between one device and the signal member for normally holding the signal member in inoperative position and operable by a passing train to permit the signal member to move to signalling position for 30 the engagement of the latch, and an operative connection between the latch and other actuating device for disengaging the latch from the signal member when the train leaves the crossing.

35 6. A signal mechanism for a railroad crossing comprising a movable signal member adapted to move to signalling position by gravity, means associated with the railroad track for normally moving said signal member to raised position and operable by 40 the train approaching the crossing to permit said signal member to move to signalling position, a latch for holding said signal member in signalling position, and means associated with the track and operatively connected with the latch for disengaging the 45 latch from the signal member when the train leaves the crossing.

7. A signal mechanism for railroad cross-

ings including two signal members, a latch 50 for each signal member to hold it in signalling position, actuating members associated with the track at opposite sides of the crossing to be moved toward and away from the crossing by trains approaching and leaving 55 the crossing, respectively, and operatively connected with the latches for disengaging the latches from the signal members when said actuating members are moved away from the crossing, and actuating members 60 operatively connected with the signal members and associated with the firstnamed actuating members to be operated by the firstnamed actuating members when they are moved toward the crossing, the secondnamed actuating members normally holding the signal members in inoperative position and, when actuated by the firstnamed actuating members, permitting the signal members to be moved to signalling position. 65

8. A signal mechanism for railroad crossings comprising two signal members, a latch 70 for each signal member to hold it in signalling position, arms associated with the track at opposite sides of the crossing to be swung 75 toward and away from the crossing by trains approaching and leaving the crossing, operative connections between said arms and latches for disengaging the latches from the signal members when the arms are swung away from the crossing, other arms associated with the firstnamed arms to be swung thereby when the firstnamed arms are swung toward the crossing, and spring actuated operative connections between the secondnamed 80 arms and signal members for normally holding the signal members in inoperative position and for permitting the signal members to move to signalling position when the second named arms are swung by the firstnamed arms. 85

In testimony whereof I have signed my name to this specification in the presence of two subscribing witnesses.
